[57] **CLAIM**

The ornamental design for an extruded rail for use in a curtain sided container to support the curtain and post assemblies, as shown.

DESCRIPTION

FIG. 1 is a perspective view of the extruded rail for use in a curtain sided container to support the curtain and post assemblies showing my new design; and, FIG. 2 is a cross sectional view taken along lines 2—2 of FIG. 1.

FIG. 1.

FIG. 2.
